CLAIM

The ornamental design for a surface configuration of a front bumper for a vehicle, as shown and described.

DESCRIPTION

This application is related to the following co-pending applications, of the inventor, filed on even date herewith:

Application Ser. No. (29/255,177), entitled “Surface Configuration of a Vehicle, Toy, and/or other Replicas”; and Application Ser. No. (29/255,176), entitled “Surface Configuration of a Vehicle, Toy, and/or other Replicas”.

FIG. 1 is a left, front perspective view of a surface configuration of a front bumper for a vehicle according to my novel design;

FIG. 2 is a right, front perspective view thereof;

FIG. 3 is a front view thereof;

FIG. 4 is a left side view thereof; and,

FIG. 5 is a right side view thereof.

The broken lines are for illustrative purposes only and form no part of the claimed design.
